UNITED STATES PATENT OFFICE.

FRANCIS MCKAY, OF HAMILTON, ONTARIO, CANADA, ASSIGNOR TO MERCANTILE TRUST COMPANY OF CANADA, LIMITED, TRUSTEE, OF HAMILTON, ONTARIO, CANADA.

AUTOMATIC TELEGRAPH DEVICE.

Application filed August 2, 1920. Serial No. 400,766.

This invention relates to that class of signalling or telegraphic apparatus which automatically sends, transmits or receives messages through the medium of electrical devices controlled by a rotatable member called a head. The forms of such device at present in use are very complicated in construction and operation and require to be handled by skilled operators in order to retain the sending and receiving members in unison so as to ensure a proper transmission of the message.

The principal objects of this invention are to provide a form of telegraph instrument particularly adapted for branch circuit use which will enable business houses sending and receiving messages and to provide a simple and compact machine which will be inexpensive to install and maintain and which will not require the services of a skilled telegrapher.

The principal features of the invention consist in the arrangement of an escapement mechanism which definitely times the operation of the individual sending and receiving members to ensure their operating in unison and in providing means for arresting the receiving mechanism at definite periods and means for releasing said arresting means controlled by the operation of the sending means.

In the drawings, Figure 1 is a plan view of the machine, parts thereof being broken away.

Figure 2 is a front elevation of the forward portion of the machine.

Figure 3 is a vertical sectional view through the line 3-3 of Figure 1.

Figure 4 is an elevational view taken from the left side of Figure 1.

Figure 5 is a vertical sectional view taken through the line 5-5 of Figure 1.

Figure 6 is an enlarged vertical sectional view on the line 6-6 of Figures 1 and 2.

Figure 7 is an enlarged side elevation of the mechanism shown in Figure 6 and the cam devices for operating same.

Figure 8 is an enlarged plan, in part section of the mechanism shown in Figures 6 and 7.

Figure 9 is an enlarged elevational view from the front side of the local pole changing switch for sending.

Figure 10 is a side elevational view of the switch shown in Figure 9. 55

Figure 11 is an enlarged elevational view of the switches for temporarily breaking the connection to the "line" wire.

Figure 12 is an enlarged elevational view of the mechanism for starting the escape- 60 ment vibrator.

Figure 13 is a wiring diagram.

It is known in the telegraphing art to use automatic transcribing machines but such machines are of a very complicated nature and being very expensive to install and maintain in service, they are limited to what is known as trunk line work and they therefore cannot be adapted for use on branch services. Such machines require 70 very constant attention on account of their delicacy of adjustment and even with the most careful attention they get out of step and the service is disorganized until they are readjusted. 75

In the application of this invention here shown perforated tape such as is used with the present well known automatic telegraph machines is used, such tape having a series of groups of perforations and each group representing a letter or character previously prepared by well known means. The machine herein illustrated is a compact unit which may be operated to send or receive messages whichever may be desired. 85

The machine here shown is formed with a base 1 upon which is mounted a pair of standards 2 and 3 and in these standards is journaled a selector shaft 4. Upon one end of the shaft 4 there is mounted a disc 5, which disc is formed with a cylindrical flange 6 which forms a housing for the helical spring 7, the outer end of which is secured to the flange. 90

A standard 8 is arranged in axial alignment with the selector shaft 4 and supports a stub shaft 9, the inner end of which is secured to the inward end of the spring 7. 95

A crown gear 10 is rigidly secured to the shaft 9 and closes the spring housing. A 100

cam member 11 is also rigidly secured to the stub shaft 9 and spaced a short distance from the crown gear 10. This cam is provided with the cam teeth 12 which are here shown 5 three in number. The crown gear is operated by a mechanism to be hereinafter described to rotate the shaft 9 and wind up the spring 7 and rotative action is imparted to the selector shaft 4 through the spring. 10 A block 13 is secured to the base 1 forward of the sending disc and a perpendicularly arranged block 14 is rigidly secured to the base block and is provided with a recess in one face thereof in which are slidably ar- 15 ranged the horizontal sending pins *a*, *b*, *c*, *d* and *e*, said pins being adapted to slide independently the one of the other. Between the pins *d* and *e* is arranged a cross pin 15 and each pin is recessed in the side 20 to form a limiting slot to allow the pin to move a certain definite distance. A cross pin 16 extends transversely through a similar slot formed in the pins *c* and *b* and another similar pin 17 fits into a similar slot in the upper side of the pin *a*.

A fixed synchronizing block 18 rests upon the upper side of the sending pin *a*. The inward ends of the pins *a*, *b*, *c*, *d* and *e* and the synchronizing block 18 are adapted to 25 extend inwardly toward the side of the sending disc 5 and on the periphery of the sending disc are arranged the pivotal dogs 19, each of which is formed with a bevelled surface 20 which engages the butt ends of 30 the sending pins and block 18 on the rotation of the disc.

A rounded edge 21 is arranged on the opposite side of the dog and projects over the other side of the disc 5 and is adapted 40 to operate the pole changing switch 22, the details of which will be hereinafter more fully described.

Each of the sending pins is formed with a small round end and these small ends 45 extend through a group of holes 23 arranged in a perpendicular plate 24 secured to the base block 13, the spacing of said holes corresponding to the spacing of the grouped holes in the tape. A guide plate 25 is se- 50 cured to the forward side of the plate 24 covering these holes and having its inner face spaced a short distance from the face of the plate 24 and forms the guide for the perforated tape.

55 A sprocket wheel 26 extends through a slot 27 in the plate 24 arranged between two of the holes 23. This sprocket is mounted on a shaft 28 supported in suitable bearings on the plate 24.

60 A locking ratchet wheel 29 is secured to the lower end of the shaft 28 and a ratchet wheel 30 is arranged on its upper end.

Each of the pins *a*, *b*, *c*, *d* and *e* is pro- 65 vided with a laterally extending pin *x* and to these are connected small spiral springs

x' which are connected to the plate 24 and are adapted to pull the pins *a*, *b*, *c*, *d* and *e* through the perforations in the tape.

The significance of the synchronizing block 18 will be fully described following 70 a further description of other portions of the machine.

A restoring member 31, which is in the form of a bar, is arranged at the front side of the pins *x* and is pivotally supported at 75 the top and bottom on the pin 32 and is adapted to engage the pins *x* to push the pins *a*, *b*, *c*, *d* and *e* back clear of the tape to allow it to be moved.

The restoring bar is formed with a lug 80 end 33 which is engaged by a swinging member 34 pivotally supported at the bottom of the block 14 and this swinging member is operated by the teeth 12 of the cam 11 secured on the shaft 9, a coil spring 35 holding the spur member 36 of the member 34 in contact with the cam consequently as the cam rotates, the teeth 12 rock the member 34, which in turn operates the restoring bar to return the pins A, B, C, D or E to 85 normal.

A ratchet dog 37 is pivotally mounted on the top end of the member 34 and is adapted to engage the ratchet wheel 30 to rotate the shaft 28 and operate the sprocket wheel 26 to feed the perforated tape, each movement of the cam turning the ratchet wheel one tooth and moving the tape forward a definite distance which corresponds with the 90 space between the vertical rows of perforations.

The pole changing switch 22 is provided with a pivotal arm 50 which has an arc-shaped portion 51 so placed as to be engaged by the rounded end 21 of the dogs 19 on the sending disc 5 as the disc revolves and bevelled portion 20 of the said dogs engage and ride over the butt ends of the synchronizing block 18 and the sending pins *a*, *b*, *c*, *d*, *e*. The arm 50 in turn engages and actuates the swing member 52 which is provided with electrical contacts 53 and 54 connected respectively with opposite poles of the local batteries 55 and 56 (Fig. 13). The position of the sending pins is determined by the arrangement of each group of perforations in the tape, that is to say, wherever a perforation in the tape registers with a pin, the pin enters the perforation and the butt end is moved out of the path of the dogs 19, consequently as the disc 5 rotates, the bevelled end 20 of the dog engages and rides over the first pin which has not been moved and the portion 21 engages and operates the arm 50 to tilt the contact member 52 which sends a pulse over the line and where a pin has been moved the dog drops into the depression and the member 50 operates the member 52 to send a pulse of the opposite 100 110 120 125 130

polarity over the line in the same manner as an ordinary key is operated by hand.

The wires 57 and 58 leading from the pole changing switch 22 are connected with 5 a pole changer 59 which operates to transmit the impulses to the main line from the main line battery 60.

It will be noted that after the dog 19 has cleared the sending pins *a*, *b*, *c*, *d* and *e*, it 10 will be in the "down" position, that is the position of farthest travel away from the switch 22 and which we will for clearness of description assume to send a "minus" impulse although its actual polarity is not essential and depends entirely upon the connection to the battery.

In the further movement of the sending disc 5, the next succeeding dog 19, before passing over the sending pins to originate 20 another character or signal, encounters the synchronizing block 18 and is moved to engage the switch 22 and send an impulse of opposite polarity to the line, the function of which is to synchronize the receiving device 25 with the sending device as will be described in connection with the description of the receiving device.

The mechanism for receiving impulses sent from one machine to another is here 30 shown arranged at the opposite end of the selector shaft 4 to that on which the sending apparatus is located, and the sending apparatus of one machine is electrically connected with the receiving apparatus of the other machines. It may of course be preferred to use sending and receiving machines not mechanically connected but the present arrangement shows a compact form of a combined sending and receiving machine.

40 The receiving device is here shown as arranged to operate a series of selector bars *a'*, *b'*, *c'*, *d'*, *e'* which are slidably arranged in the standards 2 and 3. (Fig. 3.) These bars are spring actuated to slide longitudinally against a stop member 62 arranged adjacent to the standard 2. This stop member is pivotally supported and forms a restoring member for returning the bars to their normal position.

45 Each of the selector bars is formed with a ratchet notch 64 in the end projecting beyond the standard 3 and a plurality of ratchet bolts 65 are supported on the standard 3 and are spring operated to engage the notches.

The receiving disc 61 (Fig. 3) carries pivotal dog members 66 here shown three in number. These dog members each have a tail portion 67 adapted to engage the ratchet 60 bolts 65 to push them down and release the selector bars and at the other side of the disc, these dogs each have an operating lever 68 which passes beneath the T end 69 of the tripping member 70. The tripping member 65 70 is pivotally supported on a standard 71

and carries an armature 72 which is operated by the magnet 73.

A receiving polar relay 74 (Fig. 13) is connected with the line wire and operates to direct the current from the local battery 75 70 to the magnet 73 according to the sequence of the pulses received, the lever 70 actuating the dog 66 so as to release the appropriate selector bar or bars.

The receiving disc 61 is provided with 75 radial stops 76 (Fig. 4) here shown three in number, and these stops are adapted to engage a latch member 77 which is pivotally supported from the base and is spring held 80 to engage the stops to hold the disc from rotation. The latch is provided with an armature 78 operated by a magnet 79 connected with the local battery 75 through the synchronizing switch 80 which consists of a pair 85 of magnet coils 81 and 82 arranged one at each side of a pair of adjacently arranged armatures adapted to spring together when either is released and close the circuit through the magnet 79.

The synchronizing switch is operated by 90 any change in polarity on the main line through the action of the polar relay 74, thus ensuring the release of the receiving disc 61 at the proper time as will be fully explained when the sequence of the various 95 steps in the operation is described.

Upon the release of the disc 61, the selector shaft is rotated by the tension of the coil spring 7 to effect the operation of the latch bolts 65 and as the pulses pass through the magnet 73 when it is switched into the receiving connection and in parallel with the synchronizing switch coil 81, by the manipulation of the circuit changing switch 83, the dogs 66 passing under the tripping member 100 105 70 will be operated to trip certain of the latches and release certain of the selector bars according to the pulses received.

The switch 83 is connected with the coils 110 81 and 82 of the synchronizing switch in such a manner that the operator may connect them instantaneously into either the sending or receiving circuit so that the sending machine will control the synchronizing switch on both the sending and receiving 115 machines.

When the dogs 66 have passed clear of the tripping member the disk continues to rotate until the next succeeding stop 76 on the disc engages the latch 77. This arrests the 120 receiving mechanism until the next series of pulses is transmitted.

In the operation of the disc 61 it is necessary to control its movement and to divide such movement into well defined periods. 125 In order to accomplish this an escapement mechanism is provided. On the shaft 4 is arranged a toothed escapement wheel 84 which is here shown provided with three separate sets of teeth, one set for each dog 130

on the disc 61 and each set containing three teeth. Adjacent to the shaft 4 is arranged a pivotal arm 85 supported upon a pivot secured to the base and adapted to swing transversely in relation to the wheel 84. Upon this arm is arranged a pair of escapement pallets 86 adapted to enter between the escapement teeth. These pallets are stepped downwardly so that each tooth of the escapement wheel first engages the upper pallet and as the arm is swung laterally it engages the lower pallet, thus making six points of a dead beat escapement, stopping each tooth of the escapement twice.

10 The arm 85 is provided with an armature 87 which is operated by a magnet coil 88. Electrical pulses are passed through the coil to attract the armature and then release it and a spring 89 swings the arm away from the magnet.

15 The electrical pulses to the coil 88 are regulated by a vibrator which constitutes a standard 90 supporting a vibrator arm 91. This vibrator arm carries a contact 92 which co-operates with a stationary contact 93. A bar 94 is slidably supported in a bracket 95 secured to the base and this bar is provided with a hooked end 96 engaging the vibrator arm 91. (See Figures 1 and 12.)

20 The other end of the bar 94 engages a notched cam 97 arranged on the shaft 4, there being three notches in the cam corresponding with the number of sets of teeth on the escapement. The notches are so arranged that when the end of the bar 94 engaging the cam enters a notch the hooked end 96 will release the vibrator arm and start it vibrating through the tension of its own spring.

25 The vibrator thus makes and breaks contact in the circuit connected with the escapement coil, giving the necessary stop motion to the shaft.

30 The movement of the shaft as governed by the escapement is sufficient to carry the operating dog over the five ratchet bolts to effect the release of the five selector bars or such of them as are to be released. Immediately upon the dog 66 clearing the selector latches the escapement will by reason of the blank spaces be released from the control of the pallets and the disc will revolve rapidly until brought to rest by the latch 77 engaging the stop 76 in position to receive the next series of pulses.

35 The device is here illustrated as applied to a typewriting machine for transcribing the messages, though any suitable form of signal or indicating mechanism may be used in connection with the selectors.

40 In the form shown type bar levers 63 (Fig. 5) are supported in a guide comb 98 and each of these levers are formed with a notch 99 at the forward end.

45 A bail 100 extends across the top of the

type bar levers and is provided with a ratchet tooth 101 to engage the notches of the type bar levers. The bail is pivotally supported on the rod 102 and is actuated by the spring 103 to swing forward and operate the type bar levers. The bail is held however by the lever arm 104 which extends rearwardly and is engaged by a dog 105. The comb 98 is pivotally supported from a pair of pivotal arms 106 and these arms are held in spring engagement with the cams 107 arranged on a cross shaft 108.

50 As the shaft 108 is rotated the cams release the arms 106 which are spring pulled upwardly and the comb frees the type bar levers allowing them to swing upwardly through the pull of the springs 109 to engage the selector bars.

55 A pin 110 on the shaft 108 kicks the dog 105 clear of the bail lever and the bail operates whatever type bar is selected.

60 An arm 111 carried by the shaft 108 engages the bail lever and returns it to normal.

65 A shaft 112 arranged at right angles to the shaft 4 intersects the end of the shaft 108 and a driving connection is established through the bevel gears 113 and 114. The shaft 112 also carries a pinion 115 which operates with the crown gear 10 to wind up the spring 7 and adjacent to the pinion 115 is arranged a cam 116. This cam operates an arm 117 which is connected with the restoring arm 62.

70 A collar 118 is slidable on the shaft 112 and rotates therewith. One end of this collar is formed with a tooth 119 and the adjacent bearing is provided with a notch 120 into which the tooth 119 is adapted to fit. The opposite end of the collar is provided with a plurality of clutch teeth 121 adapted to engage a correspondingly notched member 122.

75 A bell crank arm 123 is operatively connected with the collar to slide it on the shaft to bring the teeth 121 into engagement with the teeth 122. This movement lifts the tooth 119 out of the notch 120 and ensures the clutch teeth remaining in contact for one revolution of the shaft 112.

80 The bell crank arm is operated by means of a magnet coil 124. This magnet coil receives its current through a switch member 125, (see Figs. 3 and 11) which is operated by a cam 126 arranged on the receiver end of the shaft 4. This cam closes the switch 120 immediately following the transmission of the last pulse of each series and the clearing of the latch bolts by the operating dogs, thus throwing the printing mechanism into operation.

85 When one complete revolution of the printing mechanism is effected the tooth 119 drops into the notch 120 and releases the clutch.

90 A switch 127 is arranged on the sending

end of the shaft 4 operated by a cam 128 on said shaft. This switch is arranged in the local sending circuit and cuts out the battery connected with the pole changer, that is to say, it cuts out the local battery which operates the sending pole changer. This cut-out occurs immediately following the commencement of operation of the printing mechanism and ensures the continuance of the printing operation without interruption and prevents the sending of further pulses to line until the selector bars have been restored to their normal positions by the operation of the member 62.

In the operation of this mechanism, each installation is preferably provided with a suitable form of signal to enable one operator to notify another that he desires to send a message. The operator so called will then move his switch 83 to the receiving position while the sending operator will move his to the sending position. The movement of the switch 83 at the receiving end to the position shown in the drawings, connects the synchronizing switch coil 81 in parallel with the selector coil 73 and concurrently the coil 82 of the synchronizing switch is connected with the opposite circuit controlled by the receiving polar relay 74. The receiving operator then moves the tongue of his polar relay 74 to a predetermined position which according to the wiring diagram would be the position against the right hand stop which for convenience is designated the minus side.

As the sending disc comes into operation one of the dogs 19 on the disc 5 will engage the block 18 or the sending pins *a*, *b*, *c*, *d* and *e* and a pulse will be transmitted over the main line to the receiving relay 74 of the other machine. The operation of the relay 74 de-energizes the coil 82 and the synchronizing switch 80 closes momentarily and sends a pulse through the coil 79 which operates the latch 77 simultaneously in both the sending and receiving machines and the shaft 4 of both machines are released and rotate, their movement being positively controlled by their respective escapement mechanisms and both machines move in perfect unison.

Prior to starting the machine, the perforated tape is inserted into the sending machine to bring the first line of perforations into line with the sending pins *a*, *b*, *c*, *d*, and *e* and according to the arrangement of the perforations certain of these pins will pass through the tape and when the latch 77 is released the disc 5 rotates and one of the dogs 19 operates the pole changing switch 22 in the manner described, thereby sending either plus or minus pulses over the line. These pulses being transmitted to the main line through the sending polar relay 59.

The pulses received in the receiving polar relay 74 are transmitted to the selector coil 73 and synchronizing coil 81 and the tripping armature is thus operated to operate the dog 66 carried by the disc 61 on the receiving machine. This operates in unison with the dog on the sending disc and releases certain of the latch bolts 65, causing the operation of certain of the selector bars *a'*, *b'*, *c'*, *d'* or *e'*.

Immediately the dog 66 passes over the last of the latch bolts 65, the cam 126 on the selector shaft 4 closes the switch 125. This closes an electric circuit to the magnet coil 124 operating the bell crank arm 123 and 80 throws the clutch 122 into operation.

As the pulse is but momentary, it is necessary to provide means to maintain the clutch in contact and the tooth 119 being lifted out of the notch 120 holds the clutch 85 in contact for a complete revolution. The shaft C is driven by a suitable motor, which is not shown, and operates the shaft 112 through the clutch. Concurrently, this operates the transverse shaft 108 and upon the rotation of this shaft the cams 107 release the arms 106, moving the comb 98 upwardly to clear the type bar levers allowing the selected lever to move upwardly to engage the bail. The bail is then 95 released by the operation of the dog 105 operated by the pin 110 and the spring actuated bail then functions to operate the type bar and print the selected letter, a suitable carriage D being arranged on the machine.

Concurrently with this operation the cam 116 operates the arm 117 to move the restoring member 62 inwardly and restore the selector bars to their normal position in 105 engagement with the ratchet bolts.

The driving shaft 112 operating through the pinion 115 operates the crown gear concurrent with the operation of the transverse shaft 108 and the spring 7 is rewound, 110 the shaft 4 having been arrested in its rotative movement by the latch 77 engaging the next succeeding stop on the disc 61.

Concurrent with the rotation of the crown gear the cam 11 on the stub shaft 9 operates 115 the pivotal member 34 to swing forwardly. This movement operates the restoring bar 31 to restore the pins *a*, *b*, *c*, *d* or *e* to their normal positions. Concurrently the ratchet dog 37 engages the ratchet wheel on the upper end of the shaft 28 rotating it the distance of one tooth and turning the sprocket wheel 26 to feed the tape to bring the next series of holes opposite to the sending pins.

The switch 127 of the sending end of the shaft 4 breaks the local circuit on the sending end so that no pulses can be sent to the main line while the printing mechanism is 130 in operation. This switch automatically

closes immediately following the operation of the restoring bar and the machine is ready for the next selection.

The sending pins *a*, *b*, *c*, *d*, and *e*, then 5 operate automatically according to the perforation of the tape and transmit pulses to the main line which are picked up by the receiving mechanism which does the selecting and printing.

10 After each series of perforations passes from the zone of the points of the sending pins, it is important and essential to the proper operation of the device that there be a reversal of the polarity on the main line affecting both synchronizing coils on the sending and receiving machines in order that the synchronizing latch will be operated at the proper time. This is effected by means of the bar 18 arranged above the sending pins which will always engage the dog of the disc 5 before it comes into the path of the pins *a*, *b*, *c*, *d*, *e* and effects a change 15 of polarity to release the latch of the receiving disc.

20 25 When the synchronizing latch is released the shaft 4 rotates under the influence of the spring 7 but its motion is definitely restricted by the dead beat escapement mechanism described which corresponds exactly 30 with the movement of the dog 66. The escapement mechanism is brought into operation by means of the cam 97 on the selector shaft 4 operating the bar 94 to release the vibrator arm.

35 An apparatus such as described is of extremely small compass, being about the size of an ordinary typewriter. It is a self-contained unit and can be handled very easily. It is inexpensive and can be installed almost 40 anywhere a telegraph instrument is required and it will transmit directly without the services of a skilled operator any messages sent from any place.

45 It will be noted that the sending and receiving machines automatically synchronize before every series of pulses, that is to say, the machines are automatically stopped by the latches 77 after the transmission of the necessary pulses to form one letter, signal or character and there is a period of rest between the stopping to allow the printing mechanism to act. Then the next series of 50 pulses is sent. The intervening period will allow for any variation in the speed of the operating motors, consequently the machine will continue to operate practically indefinitely without attention.

55 All the operating mechanisms are operated by simple electromagnets and the whole device is free from electrical complications, all circuits being extremely simple and easily followed.

60 The machine herein described is small and very compact in form, being about the size 65 of an ordinary typewriter and constitutes a

combination sending and receiving machine which may be operated without the necessity of expert training and on account of these special conditions of universal use a most desirable structure is produced.

70

What I claim as my invention is:—

1. In a telegraph machine, a rotatable element, means for controlling the rotation of said elements, springs means for rotating said element, means for periodically rewinding said spring to maintain it at a uniform torsion, and a selective mechanism operating in mechanical co-operation with said rotatable element.

75

2. In a telegraph machine, an intermittently operating rotatable element, means for controlling the operation of said element, spring means for rotating said element, a selective mechanism operating in mechanical cooperation with said rotatable element, and means for intermittently applying torsion to said spring during its periods of rest.

80

3. In a telegraph machine, an intermittently operating rotatable element, means for controlling the operation of said element, spring means for rotating said element, a selective mechanism operating in mechanical cooperation with said rotatable element, and means operating during the periods of rest of said rotatable element and applying torsion to the spring equivalent to the torsion expended by the spring in the periods of movement of the rotatable element.

85

4. In a telegraph machine, a rotatable element, a selective mechanism operating in mechanical cooperation with said rotatable element, means for periodically arresting the movement of said element, means for governing the speed of movement of said element, spring means for rotating said element, and means for periodically rewinding said spring to maintain it at a uniform tension.

90

5. In a telegraph machine, a rotatable element, a selective mechanism operating in mechanical cooperation with said rotatable element, electrically controlled means for arresting the movement of said element, means for governing the speed of movement of said element, spring means for rotating said element, and means for periodically rewinding said spring to maintain it at a uniform tension.

95

6. In a telegraph machine, an intermittently operating rotatable element, a selective mechanism operating in mechanical cooperation with said rotatable element, means for controlling the operation of said element, a helical spring having one end secured to said element, a member secured to the other end of said spring and rotatable independently of the aforesaid member, and means for operating the latter rotatable member when the aforesaid rotatable member is at rest.

105

7. In a telegraph machine, means for transmitting electric pulses, a rotatable ele-

110

115

120

125

130

ment, spring means for rotating said element at a uniform speed and torque, means carried by said rotatable element for operating said transmitting means, a perforated message tape, and means controlled by said tape adapted to co-operate with the means carried by said rotatable element for operating the transmitting means.

8. In a telegraph machine, means for transmitting electric pulses, a rotatable element arranged adjacent to said transmitting means, movable members carried by said rotatable element adapted to be moved to engage or to pass said transmitting means, means arranged adjacent to said rotatable element adapted to engage said movable members carried by the rotatable element, and a perforated message tape controlling the movement of the latter movable members.

9. In a telegraph machine, means for transmitting electric pulses, a rotatable element arranged adjacent to said transmitting means, pivotal dogs mounted on said rotatable element and adapted to swing transversely thereof, a plurality of pins arranged in the path of said pivotal dogs adapted to engage and move them to operate the transmitting means, means for moving said pins out of the path of said dogs, and a perforated message tape controlling the movement of said pins.

10. In an automatic telegraph device the combination with a perforated message tape having spaced groups of perforations, a plurality of pins adapted to enter the ends of said perforations in said tape, said pins being parallelly arranged and slidable in relation to each other, a rotatable member arranged adjacent to said pins, a pivotal member carried by said rotatable member across said pins and adapted to be swung on its pivot according to the location of said pins as defined by the perforated tape, a pole changing switch adapted to be operated by said pivotal member in its passage over said pins and adapted to send pulses to the line wire indicating certain characters.

11. In an automatic telegraph device the combination with a perforated message tape having spaced groups of perforations, a plurality of pins adapted to enter the ends of said perforations in said tape, said pins being parallelly arranged and slidable in relation to each other, a fixed block arranged at the initial end of the row of pins, a rotatable disc mounted adjacent to said pins, members carried by said rotatable disc adapted to be engaged by said block or said pins when they are not entered into perforations in the tape, and a pole changing switch adapted to be operated by the members carried by said disc to send pulses to the line wire.

12. A telegraph transmitter, comprising a

rotatable member, spring means for rotating said member, means for regulating the speed of rotation of said member, means for periodically arresting said member, a guide arranged adjacent to the periphery of said rotatable member having a recess therein, a plurality of sending pins slidably arranged in said recess in said guide and adapted to slide independently the one of the other, pivotal dogs mounted on the periphery of said rotatable member and having a spur projection adapted to engage said sending pins, a pole changing switch having a shoe arranged in the opposite side of said rotatable member and adapted to be engaged by said pivotal dogs when in contact with said sending pins, means for moving said sending pins out of the path of said dogs to allow said dogs to move without operating the switch, and a perforated tape adapted to control the movement of said pins.

13. A telegraph transmitter, comprising a rotatable member, spring means for rotating said member, means for regulating the speed of rotation of said member, means for periodically arresting said member, a guide arranged adjacent to the periphery of said rotatable member having a recess therein, a plurality of sending pins slidably arranged in said recess in said guide and adapted to slide independently the one of the other, a fixed synchronizing block arranged at one end of the row of pins, pivotal dogs mounted on said rotatable member having spur ends adapted to first engage said synchronizing block and to be swung thereby on their pivots and to then pass over the several sending pins or through the spaces vacated by said pins, a pole changing switch arranged adjacent to said sending pins having a shoe arranged parallel with the face of the pins and adapted to be engaged by said dogs when said dogs engage the synchronizing block or the sending pins and to remain at rest where a sending pin is withdrawn from the path of movement of the dog.

14. A telegraph transmitter, comprising a rotatable member, spring means for rotating said member, means for regulating the speed of rotation of said member, means for periodically arresting said member, a guide arranged adjacent to the periphery of said rotatable member having a recess therein, a plurality of sending pins slidably arranged in said recess in said guide and adapted to slide independently the one of the other, individual spring means for drawing said pins longitudinally away from said rotatable member, a perforated tape governing the movement of said pins, means for limiting the movement of said pins, means for returning said pins against the tension of their springs, dogs mounted on said rotatable member and adapted to be moved transversely thereof to engage said

pins and to be moved transversely by said pins, and a pulse sending member adapted to be engaged by said dogs when said dogs are engaged by said pins.

- 5 15. In a telegraph machine, a controlled rotatable element, spring means for rotating said element, means for periodically arresting said element, means for applying torsion to said spring during the periods of 10 rest of the rotatable element, means carried by said rotatable element for effecting the transmission of pulses, means arranged adjacent to said rotatable element adapted to control said pulse sending means, a perforated tape governing said controlling means, and means actuated by the means for applying torsion to the spring for moving said tape at defined intervals.

16. In a telegraph machine, a controlled 20 rotatable element, spring means for rotating said element, means for periodically arresting said element, means for applying torsion to said spring during the periods of rest of the rotatable element, means carried 25 by said rotatable element for effecting the transmission of pulses, means arranged adjacent to said rotatable element adapted to control said pulse sending means, a perforated tape governing said controlling 30 means, a sprocket wheel engaging perfor-

ations in the tape, a shaft supporting said sprocket wheel, a ratchet wheel on said shaft, a dog adapted to engage said ratchet wheel, a pivoted member supporting said dog, and means carried by the torsion applying means for swinging said pivotal member to operate said dog.

17. In a telegraph machine, a controlled rotatable element, spring means for rotating said element, means for periodically arresting said element, means for applying torsion to said spring during the periods of rest of the rotatable element, means carried by said rotatable element for effecting the transmission of pulses, pins arranged adjacent to said rotatable element adapted to control said pulse sending means, a perforated tape governing said controlling pins, means for moving said pins individually, a bar pivotally mounted adapted to engage any of said pins to return them to their normal position, a rotatable cam member connected with the means for applying torsion to the spring, a rockable member adapted to be rocked by said cam and to engage and operate said bar to return said sending pins, and means operated by said rockable member adapted to advance the tape at regular intervals.
